UNITED STATES PATENT OFFICE.

LORENZ OBERLANDER, OF BALDWINSVILLE, NEW YORK, ASSIGNOR OF THREE-FOURTHS TO JACOB C. KENYON, OF SAME PLACE, AND GEORGE L. BROWN AND REUBEN J. GETZ, OF BUFFALO, NEW YORK.

CAR-COUPING.

SPECIFICATION forming part of Letters Patent No. 351,123, dated October 19, 1886.

Application filed September 7, 1886. Serial No. 212,897. (No model.)

To all whom it may concern:

Be it known that I, LORENZ OBERLANDER, of Baldwinsville, county of Onondaga, in the State of New York, a citizen of the United States, have invented certain new and useful Improvements in Car-Couplings, of which the following is a specification, reference being had to the accompanying drawings, in which—

Figure 1 is a plan view of the parts in their coupled position; Fig. 2, a longitudinal section taken on line *x x*, Fig. 1; Fig. 3, an end view, and Fig. 4 a detail view, of coupling-hook.

Similar letters and figures of reference indicate corresponding parts throughout the several views.

The object of my invention is to produce an improved car-coupling, operating automatically in coupling the cars together, and uncoupled by a lever mechanism operated from the side of a freight-car or from the platform of a passenger-coach.

It is constructed as follows: A is the frame of the car, shown in the drawings as that of a freight-car, and in which the bumper B is mounted in any ordinary manner, the draw-bar being provided with a spring and a retaining-nut in the ordinary manner. The body of this bumper consists of an upper plate, 1, a lower plate, 2, and a plate, 3, connecting them to each other at their rear ends and also to the draw-bar. The front ends of these body-plates are connected by the bolts or pins 4 and 5. The space between these plates should be wide enough to cover the variation in the heights of the bumpers in different cars. The pins 4 are shown in the drawings as constructed with the lower end larger than the top, and with a shoulder or its equivalent.

C is my coupling-hook, consisting of a flat body, 6, provided with a side arm, 7, having upon its outer end a head, 8, standing at an angle to the line of the arm, which head extends or projects both above and below the arm, substantially as shown, and also provided with a point, 9, rounded and beveled back to and forming the hook 10. Between this hook and arm I locate the hole to receive the pivot-pin 4, fitting loosely thereon and resting upon its shoulder. In the rear end of

this coupler I make a hole or holes, 11, to receive one end of the spring 12, and also of the chain 13. The other end of the spring 12 is secured to one of the frame-timbers. The outer end of the chain 13 is led outward over 55 an idler, 14, and thence upward to and is connected to the handle 15, which is fulcrumed upon the side of the car, substantially as shown.

The top plate of the bumper passes through 60 the hangers 16, and has an endwise movement therein.

A bail, 17, is thrown over the inner part of the coupler to prevent its flopping up or down.

It is operated as follows: Taking the parts 65 in position, as shown in Fig. 1, coupled together, to uncouple them I press down the lever-handle 15, and this, through the chain 13, draws the inner end of the coupler on that car inward. As this movement continues, the 70 head 8 of this coupler encounters the hook (or beveled end) of the other coupler and wedges the hook out of engagement with the pin 5. At the same time this motion operates to draw the other hook out of its engagement with its 75 pin 5. In fact, whenever either handle is operated, the heads 8 of the couplers engage with the adjacent hooks and both hooks are disengaged simultaneously. In coupling cars together the beveled points of the hooks first 80 encounter the pins 5 and wedge past them until the springs 12 throw the hooks into engagement with the pins 5. In the bumper-plates I also make holes 18, to be used with an ordinary link-and-pin coupling whenever it may 85 be necessary. The heads 8 are elongated vertically in order to insure their proper engagement with the couplers, as described, when one bumper is higher than the other.

Having thus described my invention, what I 90 claim as new, and desire to secure by Letters Patent, is—

1. A car-coupling consisting of the reciprocating couplers C, pivotally mounted in the bumpers and engaging with pins therein, and 95 provided with an operating-lever connected to each coupler, in combination with the bumpers B and frames A, substantially as shown and described.

2. A car-coupling consisting of two coup- 100

lers, C, each provided with a beveled hooked point, and a side arm provided with a head, 8, and pivotally mounted in the bumpers, and each connected to an operating-lever on the outside of the car, in combination with the bumpers B, provided with pins 4 and 5, mounted in the car-frames, substantially as shown and described.

In witness whereof I have hereunto set my hand this 2d day of September, 1886.

LORENZ OBERLANDER.

In presence of—

Wm. C. RAYMOND,
L. F. SMITH.
